(57) **CLAIM**

The ornamental design for a catheter handle, as shown and described.

DESCRIPTION

FIG. 1 is a perspective view of a catheter handle according to the present invention with a stress relief embodiment.

FIG. 2 is a top side, elevational view of the catheter handle for the catheter shown in FIG. 1.

FIG. 3 is a bottom side, elevational view of the catheter handle for the catheter shown in FIG. 1.

FIG. 4 is a first end plan view of the catheter handle shown in FIG. 1; and,

FIG. 5 is a second end plan view of the catheter handle for the catheter shown in FIG. 1.

The portions of the design shown in broken lines are provided for illustrative purposes only and form no part of the claimed design.

1 Claim, 3 Drawing Sheets

FIG. 2

FIG. 3

FIG. 4

FIG. 5
